UNITED STATES PATENT OFFICE.

THEODOR C. FEDDERS, OF BUFFALO, NEW YORK.

RADIATOR FOR COOLING LIQUIDS.

No. 881,392.

Specification of Letters Patent. Patented March 10, 1908.

Application filed June 3, 1905. Serial No. 263,564.

To all whom it may concern:

Be it known that I, THEODOR C. FEDDERS, a citizen of the United States, residing at Buffalo, in the county of Erie and State of New York, have invented a new and useful Improvement in Radiators for Cooling Liquids, of which the following is a specification.

This invention relates to the radiators which are used for cooling the water which is circulated around the cylinders of explosive engines, for instance, those used on automobiles, and more particularly to that class of radiators which comprise tubes which are open at their ends to the atmosphere and are separated by narrow flow spaces for the water to be cooled. It is important in radiators of this kind that the metal of which the tubes are made, copper, for instance, should be as thin as possible, consistent with strength and rigidity, in order to give the tubes a proper capacity for conducting heat.

The object of this invention is to construct the radiator in such manner that very thin metal can be used for the tubes and that the tubes, nevertheless, will be stiff and rigid and preserve their form, and will furnish a large radiating surface.

In the accompanying drawings, consisting of two sheets: Figure 1 is a front elevation of a radiator provided with my improved tubes, the latter having their flanges arranged vertically. Fig. 2 is a vertical transverse section through one of the upper corners of the radiator, on an enlarged scale. Fig. 3 is a horizontal section in line 3-3, Fig. 2. Fig. 4 is a vertical longitudinal section in line 4-4, Fig. 2. Fig. 5 is a similar section enlarged. Fig. 6 is a fragmentary top plan of several of the tubes. Fig. 7 is a fragmentary perspective view of one of the tubes. Fig. 8 is a fragmentary perspective view of one of the filling pieces. Fig. 9 is a front elevation of one of the lower corners of a radiator having the tubes arranged with their flanges horizontally. Figs. 10 and 11 are perspective views of the sheet metal blanks of which the flanged tubes are formed. Fig. 12 is a front elevation of a number of tubes which have no side flanges. Fig. 13 is a fragmentary perspective view of one of these tubes.

Like letters of reference refer to like parts in the several figures.

The frame of the radiator may be of any usual or suitable form and construction and

comprises, as shown, an upper water inlet chamber A, a lower water exit chamber B, and upright side pieces C, forming together a frame which has a rectangular inner space 60 in which the stack of horizontal tubes D is arranged. These tubes are square or rectangular in cross section, open at their front and rear ends to the atmosphere, and are arranged preferably in horizontal rows with 65 the tubes in one row standing opposite the spaces between the tubes in the next upper and lower rows, so that the upright water passages between the tubes are staggered. The tubes have plain end portions e and are 70 provided between these end portions with transverse grooves or channels f which are 75 preferably of shallow, concave form in cross section.

In the preferred construction of the tubes, 75 represented in Figs. 1-11, each tube is formed of two blanks G G', Figs. 10 and 11, bent to form flanged channels which, when secured together by their flanges, form a four-sided tube having projecting, longitudinal flanges h at the middle of two opposite sides. Each of the blanks G G' is transversely grooved or corrugated, as shown at f, between the plain end portions e and has plain side portions g g', respectively, which, 80 when secured together, form the flanges h. The plain side portions of one blank are so much wider than the plain side portions of the other blank that upon putting the flanged channels against each other the wide flanges 85 can be closed around the narrow flanges to form hook joints or seams. This seam is preferably soldered to insure a water tight joint. These tubes may be arranged in the radiator frame with their flanges standing either vertically or horizontally but the vertical arrangement is preferred because it produces a 90 more pronounced staggering of the flow passages between the tubes.

The spaces between the inner side of the 100 radiator frame and the adjacent rows of tubes from which the flanges h project toward the frame are closed by metallic filling strips I which are fitted with their outer sides against the frame and with their inner side against the tubes and are provided on their inner sides with slots i for the reception of the flanges. These strips are soldered to the frame, or otherwise secured thereto, and practically form parts of the frame. The 105 end portions of the tubes are soldered to these strips. When the tubes are arranged 110

with their flanges in a perpendicular position, as shown in Figs. 1-8, the uppermost and the lowermost rows of tubes have their flanges projecting toward the frame and are secured 5 to these filling strips, which latter are arranged horizontally against the inner sides of the front and rear walls of the upper and lower water chambers. When the tubes are arranged in vertical rows and with their 10 flanges horizontally, as represented in Fig. 9, the filling pieces are arranged vertically against the inner sides of the upright side pieces C of the frame. The spaces at the ends of those rows of tubes which do not extend 15 quite to the frame may be filled with channel pieces D'. The spaces between the plain ends e of the tubes and the spaces between the longitudinal edges of the outermost tubes at the sides of the stack of tubes are closed by 20 solder, so that, when the stack of tubes is secured in the rectangular opening of the frame, the upper water chamber A will communicate with the lower water chamber B only through the flow passages between the 25 tubes. The plain ends of the tubes are secured to the frame of the radiator by soldering.

The flow passages between those portions of the tubes which are not separated by the flanges h are divided by the sides of opposing 30 grooves or channels into numerous small spaces, each of which is practically inclosed by the metal of adjacent tubes, and through which the water flows in small thread-like bodies. When the flanges are arranged 35 vertically, as shown in Figs. 1-11, the horizontal portions of the tubes are in direct contact by means of the ridges between their grooves or channels, while the upright portions of the tubes are separated by the interposed flanges. These flanges cover the 40 grooves or channels in the upright sides of the grooves part way and divide each flow space into two parts which unite into one flow space between those upright portions of 45 the tubes which are not covered by the flanges. The transverse grooves or channels stiffen the tubes, increase the radiating surface, enable the tubes to yield under the action of freezing, and support the tubes at 50 numerous points in their length when assembled in the radiator. The longitudinal flanges further increase the stiffness of the tubes and the strength and rigidity of the assembled stack of tubes. These qualities 55 of the tubes permit the use of comparatively

thin sheet metal, whereby the cooling capacity is increased, and the formation of the tubes from flat blanks having their longitudinal edges connected by seams also aids in permitting the use of very thin sheet 60 metal.

In the construction of the tubes represented in Figs. 12 and 13, each tube D² is made of a single blank of sheet metal which has its longitudinal edges secured together 65 by a lock seam k arranged on the inner side of the tube and preferably soldered to insure tightness. These tubes rest against each other with their plain end portions e, where they are secured together by soldering, and 70 they also rest against each other at intermediate points by the ridges between the grooves or channels f. The end portions of the outermost tubes are secured to the frame and filling pieces are not required. 75

I claim as my invention:

1. A radiator comprising open-ended prismatic tubes having plain end portions by which the tubes rest against each other and having between said end portions alternating 80 channels and ridges which are arranged crosswise with reference to the longitudinal dimension of the tubes, substantially as set forth.

2. A radiator tube composed of two channel-shaped parts having their longitudinal flanges seamed together and having between said flanges alternating channels and ridges which are arranged crosswise with reference 90 to the longitudinal dimension of the tube, 90 substantially as set forth.

3. A radiator comprising a frame having upper and lower water chambers and horizontal tubes arranged in said frame, said tubes having plain end portions by which 95 the tubes rest against each other and longitudinal flanges and having between said end portions alternating channels and ridges which are arranged crosswise with reference to the longitudinal dimension of the tubes, 100 and slotted filling strips arranged between the tubes and the frame, substantially as set forth.

Witness my hand this first day of June, 1905.

THEODOR C. FEDDERS.
